US00D983970S

(12) **United States Design Patent** (10) **Patent No.:** **US D983,970 S**
(45) **Date of Patent:** **** Apr. 18, 2023**

(54) **SURGICAL BUR ASSEMBLY**

(71) Applicant: **Stryker European Operations Limited**, Carrigtwohill (IE)

(72) Inventors: **Aidan Vaughan**, Cork (IE); **Eoin Connolly**, Dublin (IE)

(73) Assignee: **Stryker European Operations Limited**, Carrigtwohill (IE)

(**) Term: **15 Years**

(21) Appl. No.: **29/864,274**

(22) Filed: **May 17, 2022**

Related U.S. Application Data

(63) Continuation of application No. 29/747,317, filed on Aug. 21, 2020, now Pat. No. Des. 956,222.

(57) **CLAIM**

The ornamental design for a surgical bur assembly, as shown and described.

DESCRIPTION

FIG. 1 is a top, left-side, perspective view of a surgical bur assembly;

FIG. 2 is a top view thereof;

FIG. 3 is a bottom view thereof;

FIG. 4 is a left-side view thereof;

FIG. 5 is a right-side view thereof;

FIG. 6 is a front view thereof;

FIG. 7 is a rear view thereof;

FIG. 8 is an enlarged front, right-side, partial perspective view thereof;

FIG. 9 is an enlarged partial bottom view thereof; and,

FIG. 10 is an enlarged partial right-side view thereof.

In the drawings, the broken lines represent unclaimed portions of the surgical bur assembly and form no part of the claimed design.

1 Claim, 4 Drawing Sheets
